UNITED STATES PATENT OFFICE.

WILLIAM L. CHIPLEY, OF LA MONTE, MISSOURI.

PUMP.

SPECIFICATION forming part of Letters Patent No. 251,523, dated December 27, 1881.

Application filed October 12, 1881. (No model.)

To all whom it may concern:

Be it known that I, WILLIAM L. CHIPLEY, a citizen of the United States of America, residing at La Monte, in the county of Pettis 5 and State of Missouri, have invented certain new and useful Improvements in Pumps; and I do hereby declare the following to be a full, clear, and exact description of the invention, such as will enable others skilled in the art to 10 which it appertains to make and use the same, reference being had to the accompanying drawing, and to letters or figures of reference marked thereon, which form a part of this specification.

My invention relates to pumps; and it consists of the construction and arrangement of its several parts, as will be hereinafter fully set forth.

The accompanying drawing is a longitudinal section.

20 A is the pump. It consists of a cylinder, B, provided with a reservoir, C, upon its upper end, and a chamber, D, upon its lower or submerged end, in which is placed a valve and strainer, all being arranged substantially as 25 shown.

The reservoir C, which may be of any desired shape, has its lower end tightly secured around the upper portion of the cylinder, which projects into it, as shown, for the purpose of 30 relieving the operator of the additional weight of the water in the reservoir.

Upon the top of the cylinder is an opening, to which is fitted the screw-cap e. This screw-cap is provided with a small central opening 35 and a stuffing-box, c', through which passes the sucker-rod, as shown.

The reservoir has an outlet, d, situated in its upper side, and an outlet, d', in its lower side. The ends of these outlets have threads 40 cut around them, so that caps may be screwed onto either of them, as desired.

E is the sucker-rod. It has upon its lower end the piston b, in which operates the valve b'. Placed around the rod are the caps a. They 45 are upwardly inclined, their lower ends being secured around the rod and their upper and outer ends fitting snugly the sides of the cylinders. They have suitable perforations, a', through which the liquid may readily pass 50 when the pump is in operation.

Motion is transmitted to the rod by any of

the devices for such purpose in common use; but the lever F and pivoted rod G, fastened to the reservoir, is the method employed.

In the operation of my pump the cups a act 55 to support the weight of the column of water in the cylinder, thus relieving the strain upon the piston-valve b' and rendering the operation of the actuating-lever easier, and in the downstroke of the piston b, they being provided 60 with outlets allow the liquids to pass through them rapidly.

By the employment of the reservoir-outlets d d' the pump can be made either a lifting or 65 a force pump.

The cap can be secured onto the nozzle d', and a hose or pipe can be attached to the nozzle d. The pump can then be put in operation. The air remaining in the cylinder above the outlet of the nozzle will constitute the air-chamber, and the water can be forced through 70 the hose or pipe with a rapidity in proportion to the strength applied to the actuating-lever; or the liquid can be forced out of the nozzle d' with the same rapidity by closing the opening 75 of the nozzle d.

This pump is especially adapted for use in bored wells, where it is desired to secure a rapid and continuous flow of water through a cylinder of small diameter.

80 What I claim is—

1. The funnel-shaped reservoir C, with its lower end tightly secured around the cylinder B, and provided with an opening, d, in its upper side and an opening, d', in its lower side, 85 said reservoir being arranged to operate in combination with the sucker-rod E, its piston b, valve b', and its actuating mechanism.

2. In a lifting and force pump, the combination of the cylinder B, with valve and strainer 90 situated in its lower end, and reservoir C, having an opening in its top, and provided with outlets d and d', with the sucker-rod E, cups a, piston b, and valve b', and its actuating mechanism, all arranged and operating substantially as shown.

In testimony whereof I affix my signature in presence of two witnesses.

WILLIAM LEE CHIPLEY.
